WALL DUSTER

John Glover, Chicago, Ill., assignor, by mesne assignments, to Midway Chemical Co., Jersey City, N. J., a corporation of New Jersey

Application November 19, 1934, Serial No. 753,695

9 Claims. (Cl. 306—1)

The present invention relates to an improved wall duster or the like.

One of the objects of the present invention is the provision of an improved socket for a wall duster or the like and in which a duster unit or frame may be better secured.

A second object of the invention is the provision of a unique socket for a wall duster of simplified construction, and in which the duster unit or frame may be used in reversed positions, the socket having means for maintaining the duster frame relatively rigid in spaced-apart useful angles.

Another object of the present invention is the combination of a socket suitable for use upon a handle and having a movable sleeve in which a duster frame is held so that it is firmly gripped in a plurality of positions at the election of the user.

These objects, and such other objects as may hereinafter appear, are obtained by the novel construction, unique combination, and improved arrangement of the several elements which constitute the invention, one embodiment of which is illustrated in the accompanying single sheet of drawings, hereby made a part of this application, and in which:

Figure 1 is an elevation of a duster made in accordance with the teachings of the present invention and having a two-strand frame;

Figure 2 is a section on the line 2—2 of Figure 1 of a duster identical in structure with that shown in Figure 1 with the exception that the frame consists of three-wire strands;

Figure 3 is a view similar to Figure 2 but with the parts in reversed position; and

Figure 4 is an enlarged detail, partly in section, illustrating the manner in which the socket sleeve and duster frame are joined one to another.

Like reference characters are used to designate similar parts in the drawing and in the description of the invention which follows.

The device illustrated is a wall duster. The invention may be used with other devices. The duster illustrated is provided with a stick or handle 10. At one end of the handle 10 is a socket. The socket comprises sheet metal stamped and folded to provide a number of parts in an integral member.

Said socket, at one end, has handle encircling means 11. The means 11 describes substantially a circle about stick 10 but is open at one side where it has spaced apart ears 12 and 13 with complementary apertures 14 and 15 through which

a bolt 16 is inserted, a nut 17 being run home on the bolt 16 to secure the means or sleeve 11 firmly about the end of stick 10.

An aperture 18 may be provided in sleeve 11 through which a nail 19 or other fastening means is driven to further firmly secure the socket upon the handle. The ends of the cylindrical portion or sleeve 11 may have tangs 20 which are inwardly bent to provide stops for the end of the handle. The tangs 20 determine the position of handle member 10 in respect to the socket.

Adjacent to the cylindrical portion 11 of the socket is an arcuate extension or section 21 which may be intentionally deformed in manufacture to make its arc of a larger radius than the radius of handle encircling part 11. Through part 21 is an aperture 22 which may have a beaded rim.

Beyond the shallow arcuate section 21, there is a substantially cylindrical bearing 23, which terminates in a tongue 24 that is apertured at 25. The bearing 23 is of greater lateral extent than the shallow arcuate section 21 and the aperture 25 in the tongue 24 registers with the aperture 22 in the arcuate section 21 when assembled. When the parts are assembled, the tongue 24 fits within the internal face of the arcuate section 21. A suitable bolt 26 is inserted through the registered apertures 22 and 25, and a nut 27 is threaded on to the bolt. 30

Within the bearing 23 is a split arcuate sleeve 28. The sleeve 28 may comprise arcs that are eccentric. The sleeve 28 has at its ends beaded sections 29 and 30 which prevent its longitudinal displacement of the bearing 23 when assembled 35 therewith.

Through the sleeve 28 there extends a twisted wire frame 31 upon which the duster material 32 is secured in a conventional manner, the frame 31 being of any suitable configuration, the substantially rectangular frame shown having an inset section 33 as shown in the drawing, that is highly satisfactory. The frame shown in Figure 1 is twisted from two-wire strands while that disclosed in Figures 2, 3 and 4 has been twisted 45 from three strands.

In forming the inset section 33, the frame 31 is bent adjacent the beaded parts 29 and 30 of the sleeve 28 so that the twisted wire of the frame projects from the sleeve 28 through the 50 space produced by its split cylinder structure. The protrusion of the twisted wire through the slit in the sleeve 28 maintains the frame against rotative displacement relative to the sleeve 28 and it is impossible to move the frame at an an-

gle to its plane without a concurrent movement of the sleeve 28 save by deformation of the twisted wire frame of the duster which deformation will not normally occur.

5 Moreover the eccentric distortion of sleeve 28 is maintained and resiliently supported by the cross-sectional configuration of the frame, thus facilitating the maintenance of the frame in any of the pre-arranged positions. This action is 10 more particularly apparent in the embodiments shown in Figure 2 wherein the sleeve is distorted about a two-strand frame.

The duster is assembled by attaching duster material 32 to frame 31 and thereafter shaping 15 the frame to provide the inset 33 therein. The sleeve 28 is disposed about the frame material 31 at the innermost part of the inset section. This part should preferably be devoid of duster material 32 and may comprise the ends of the 20 free frame 31. The sleeve 28 with the twisted wire frame material protruding from the slit in the sleeve at each end thereof is inserted into bearing 23 and tongue 24 drawn against arcuate section 21 by bolt 26 and nut 27. A rivet may 25 take the place of the bolt and nut, 26 and 27, respectively. The assembled socket and frame may then be attached to stick 10.

The bearing 23 may be covered by a felt strip 34 which is generally of the same color as duster 30 material 32 and which is held in position by rivets 35 extending across its free ends.

In operation, the duster is used generally in two substantially diametrically opposed positions. Either of these positions may be attained when 35 the slit is rotated so that the sleeve 28 is moved in the bearing past the longitudinal slot which exists between the tongue 24 and arcuate section 21. Movement of the sleeve from one extreme position to the other obtained by moving 40 the slit in the sleeve past the slightly open section of bearing 23 is had with relatively slight friction. Once the slit in the sleeve has been moved beyond the slit in the bearing so that both of its open edges of the sleeve are within the 45 circular portion of the bearing, there is increased friction which tends to maintain the duster frame in any selected angular position.

Such friction is sufficient to prevent accidental displacement of the frame from any selected angle selected but not sufficient to prevent 50 an intentional change in angle from one side of the stick to the other side thereof during use.

It will be apparent that the cross-sectional configuration of the frame 31 will cause the bearing 23 to fit securely upon the sleeve 28 and assist the stop action of the sleeve 28 within the bearing 23, as well as the cooperation between the sleeve and the frame 31. If the wires are 55 twisted together in substantially triangular cross-section, as in Figures 2 to 4, a frame material is provided which is generally symmetrical and which, therefore, supports the sleeve 28 uniformly. At the same time, the support is obviously resilient and acts in large measure for 60 the resilient engagement of the sleeve 28 with the inner surfaces of the bearing 23. On the other hand, a double strand frame gives a greater measure of permanent distortion and is preferable where it is distorted to cause relatively 65 rigid maintenance of the frame in either of the predetermined angular positions.

In addition, the various configurations permit the portion of the wires adjacent the split in the sleeve to engage therewith and prevent relative rotation. Accordingly in the present organ-

ization the different elements cooperate to enhance the control of the stop action, as well as to effectively lock the frame 31 in the sleeve at points along the length thereof and furthermore to provide a structure which is of considerable 5 rigidity and strength.

The arcs in the sleeve 28 may be such that two different parts of the sleeve 28 spaced one hundred and eighty degrees apart register with the opening between tongue 24 and arcuate section 21 to provide two snap in positions, these snap in positions being generally opposed as previously stated. To dislodge the duster from either of these positions requires intentional displacement on the part of the user.

Such parts, eccentric to the main body of sleeve 28, may be preformed to provide seats for the long ends of frame 31 or if preferred, may be formed in sleeve 28 as sleeve 28 is closed over the ends of frame 31 in assembly. Said eccentric parts prevent slippage of the frame ends in the sleeve 28 as heretofore pointed out.

What is claimed as new and is desired to be secured by Letters Patent of the United States is:

1. In a duster or the like, a socket for a handle and having a noncircular bearing, a sleeve in said bearing and having in cross section the shape of eccentric arcs, and a duster frame a part of which is non-rotatably held in said sleeve. 30

2. In a duster or the like, a socket for a handle and having a bearing having in cross section the shape of eccentric arcs, a sleeve in said bearing and having in cross section the shape of eccentric arcs, and a duster frame a part of which is non-rotatably held in said sleeve. 35

3. In a duster or the like, a socket for a handle and having a bearing having in cross section the shape of eccentric arcs, a split sleeve in said bearing and having in cross section the shape of eccentric arcs, and a duster frame a part of which is non-rotatably held in said sleeve, and laterally offset from the periphery of the frame. 40

4. In a duster or the like, a socket for a handle and having a bearing having in cross section the shape of eccentric arcs, a split sleeve in said bearing having enlarged ends to prevent longitudinal displacement from said bearing and having in cross section the shape of eccentric arcs one at each side of the split in said sleeve, and a duster frame in said sleeve and having portions thereof extending through such split. 50

5. In a duster or the like, a socket for a handle having a non-circular bearing portion, said bearing portion having a plurality of arcuate recesses therein, a split sleeve in said bearing portion and having in cross section the shape of eccentric arcs and adapted to be engaged in one or more of the arcuate recesses of the bearing portion, tightening means associated with the bearing portion whereby to lock the bearing portion and the sleeve in fixed engagement, and a duster frame rigidly mounted in said sleeve. 60

6. In combination, a socket for a handle having an extension bent in the shape of a loop to 65 form a bearing and a tongue integrally extending from the free end of said loop, said bearing having non-circular cross section and being provided with arcuate recesses therein, fastening means between said tongue and a section of said 70 socket adjacent said bearing, a sleeve for holding a duster frame and having in cross section the shape of eccentric arcs providing thereon end sections adapted to be engaged in the arcuate recesses on the bearing whereby said sleeve is more 75

firmly seated in the bearing in predetermined positions with respect thereto than in other positions.

7. In combination, a socket for a handle having an extension bent in the shape of a loop to form a bearing and a tongue integrally extending from the free end of said loop, said bearing having non-circular cross section and being provided with arcuate recesses therein, fastening means between said tongue and a section of said socket adjacent said bearing, a sleeve for holding a duster frame and having in cross section the shape of eccentric arcs providing thereon end sections adapted to be engaged in the arcuate recesses on the bearing whereby said sleeve is more firmly seated in the bearing in predetermined positions with respect thereto than in other positions, said sleeve having enlarged portions at each of its ends engaging the ends of the bearing member whereby to prevent longitudinal displacement of the sleeve in the bearing.

8. In a duster or the like, a socket for a handle

and having an arcuate bearing with at least one eccentric portion, a sleeve in said bearing and having an arcuate cross section, and a duster frame, a part of which is non-rotatably held in said sleeve, said part being formed of a plurality of intertwined wires, said sleeve being eccentrically distorted about said frame and firmly supported thereby.

9. In a duster or the like, a socket for a handle and having an arcuate bearing with at least one eccentric portion, a sleeve in said bearing and having an arcuate eccentric cross sectional portion, a duster frame, a part of which is held in said sleeve, said part being a composite body structure having an eccentric cross section and being formed of a plurality of inter-twisted wires, and means in the sleeve adapted to hold the frame against rotation within the sleeve by engaging only a portion of the composite body structure held in the sleeve.

JOHN GLOVER.
